UNITED STATES PATENT OFFICE.

ADOLPH BALLENBERG, OF NEW YORK, N. Y.

CASTER.

1,170,503.

Specification of Letters Patent.

Patented Feb. 8, 1916.

Application filed October 5, 1915. Serial No. 54,172.

To all whom it may concern:

Be it known that I, ADOLPH BALLENBERG, a citizen of the United States, and residing at New York, in the county of New York and State of New York, have invented certain new and useful Improvements in Casters, of which the following is a specification, such as will enable those skilled in the art to which it appertains to make and use

10 the same.

This invention relates to casters and particularly to devices of this class designed for use in connection with heavy articles of furniture and other heavy articles having 15 tubular legs, or hollow or semi-hollow legs into which the attaching parts of the caster are inserted; and the object of the invention is to provide an improvement in this class 20 of devices whereby the casters are made detachable and are held in position by spring clamp devices which are automatic in operation, and whereby the casters may be quickly and easily attached and detached whenever necessary; a further object being 25 to provide casters of the class specified with an improved "top bearing" involving a pivot head or block loosely mounted on the top of the pintle of the caster, and in which said pintle is freely rotatable; a still further object being 30 to provide casters of the class specified which may be applied to the tubular or hollow, or partially hollow legs or supports of articles of various classes, and which may be cylindrical in cross section, 35 square or octagonal in form.

The invention is fully disclosed in the following specification, of which the accompanying drawing forms a part, in which the separate parts of my improvement are designated by suitable reference characters in 40 each of the views, and in which:

Figure 1 is a sectional side view showing my improvement applied to the tubular leg of an article of furniture or other articles; 45 Fig. 2 a sectional view at right angles to that shown in Fig. 1; Fig. 3 a transverse section on the line 3—3 of Fig. 2; Fig. 4 a partial section on the line 4—4 of Fig. 3; and, Fig. 5 a view similar to Fig. 4 but showing a 50 modification.

In the accompanying drawing, I have shown at *a* a leg or support for an article of furniture, such as a bed or any other heavy article, and I have also shown at *b* a caster comprising a yoke member *b*², a roller *b*³ mounted in the yoke member, and a pintle *b*⁴

connected with the cross head portion *b*⁵ of the yoke member *b*². In the practice of my invention, as shown in the drawing, a disk-shaped plate *c* is loosely mounted on the pintle *b*⁴ and on which the leg or support *a* rests, and said disk-shaped plate is preferably provided with a raised central portion *c*². I also provide two similar clamp devices *d* formed from spring metal plates and each of which comprises a horizontal top portion *d*², a horizontal bottom portion *d*³ and an inwardly curved U-shaped or V-shaped central portion *d*⁴, as clearly shown in Fig. 3, and the inwardly curved U-shaped or V-shaped central portions of these spring clamp devices abut as is also shown in Fig. 2, and are provided with vertically arranged slots or openings *d*⁵ through which the pintle passes.

The overlapping bottom parts *d*³ of the spring clamp devices are provided with oblong slots or openings *d*⁶ through which the pintle passes, and the top overlapping part *d*² of one of the spring clamp devices is provided with a similar slot or opening *d*⁷.

Rotatably mounted on the top of the pintle *b*⁴, as shown in Figs. 4 and 5, is a block *e* provided in the bottom thereof with a conical socket *e*² adapted to receive a conical point *b*⁶ on the top of the pintle *b*⁴, and said block is provided with a neck *e*³ which passes through the slot or opening *d*⁷ in the top overlapping part *d*² of one of the spring clamp devices *d* and through an aperture *d*⁸ in the top overlapping part *d*² of the other spring clamp device *d*, and said neck is riveted to form a head *e*⁴. The aperture *d*⁸ in the top overlapping part *d*² of one of the spring clamp devices *d* is preferably 85 made to closely fit the neck *e*³ of the block *e*, while permitting it to rotate but the slots or openings *d*⁶ and *d*⁷ are of sufficient longitudinal dimensions to permit one of the spring clamp devices *d* to freely move 100 transversely of the pintle at both the top and bottom thereof, while the other spring clamp device *d* is movable only at the bottom thereof, but in Fig. 5, I have shown both of the top overlapping parts *d*² of the spring clamp devices *d* as provided with oblong 105 slots or openings, whereby said spring clamp devices are both movable transversely of the pintle at the top and bottom thereof. The construction shown in Fig. 4, however, is preferred because of the fact that one of the top overlapping parts *d*² of one of the

105

spring clamp devices *d* serves to prevent too free movement of the block *e* on the pintle *b*⁴ and to hold it in proper operative position at all times. With this construction the pintle *b*⁴ is more free to rotate than it would otherwise be and the operation of the caster or casters is thus facilitated, the yoke in which the roller *b*³ is mounted and the pintle which is firmly connected with said yoke 10 being all free to rotate with the least possible friction.

The pintle *b*⁴ is provided just above the overlapping parts *d*³ of the spring clamp devices *d* with a collar or other suitable stop *f* 15 which also aids in holding the bottom parts of the spring clamp devices in proper position on the pintle.

In the central bottom part of the disk-shaped plate *c* is a deep semi-circular, or 20 approximately semi-circular recess *c*² in which fits a corresponding raised bearing *b*⁷ on the central top portion of the cross head *b*⁵ of the yoke of the caster, and the pintle which is formed in connection or rigidly secured to said yoke or cross head portion 25 passes upwardly through said bearing and through said recess, and the disk or plate *c* which supports the load rests on said bearing. This part of the construction, however, together with the caster, or the separate parts thereof, and the disk or plate *c* 30 form, in themselves, no part of my invention and is similar to that of other devices of this class.

When it is desired to connect my improved caster with a tubular leg or support, as shown in Figs. 1 and 2, all that is necessary is to force the pintle with the spring clamp devices connected therewith into the bottom 40 of the leg or support until said leg or support rests on the plate *c* as clearly shown in Figs. 1 and 2. In this operation, the spring clamp devices *d* present four corners both at the top and bottom thereof, or eight corners in all which press firmly on the inner 45 yoke of the leg or support, and this securely binds the caster to the leg or support and prevents any lateral movement of the caster in or on the leg or support, or any movement of said leg or support on the caster.

In the accompanying drawing, I have shown only a tubular leg or support, or a leg or support which is cylindrical or circular in cross section, but it must be understood that my improved caster attaching device or devices will operate in the same way in a square leg or support, or in an octagonal leg or support.

The spring clamp devices *d* are shown and 60 described in a prior application filed by me

September 17, 1915, Serial No. 51,139, and in themselves form no part of this invention which is limited to the bearing block *e* on the top of the pintle, and the method of connecting it with said spring clamp devices, and while I have shown the preferred form of said block and the preferred method of connecting it with the spring clamp devices and the pintle, my invention is not limited to these details of construction, and 65 various changes therein and modifications thereof may be made, within the scope of the appended claims, without departing from the spirit of my invention or sacrificing its advantages. 70

Having fully described my invention what I claim as new and desire to secure by Letters Patent, is:—

1. A caster provided with a pintle, spring clamp devices mounted on said pintle and 80 having overlapping ends, and a pivot block mounted in connection with said ends and bearing on the top of the pintle.

2. A caster provided with a pintle, spring clamp devices loosely mounted on said pintle 85 and having overlapping top ends, and a pivot block loosely mounted in connection with said ends and bearing on the top of the pintle.

3. A caster provided with a pintle, spring 90 clamp devices loosely mounted on said pintle, and having overlapping top ends, and a pivot block loosely and rotatably mounted in connection with said ends.

4. A caster provided with a pintle, an attaching means loosely mounted thereon and extending above the top of the pintle, and a pivot block rotatably mounted in said means and vertically movable therein and bearing on the top of the pintle. 95

5. A caster provided with a pintle, clamp devices mounted on said pintle and having overlapping top end members, and a pivot block supported by one of said end members and bearing on the pintle. 100

6. A caster provided with a pintle, clamp devices mounted on said pintle and having overlapping top end members, and a pivot block supported by one of said end members and bearing on the pintle, the other end member being movable transversely of said block. 105

In testimony that I claim the foregoing as my invention I have signed my name, in presence of the subscribing witnesses, this 2nd day of October, 1915.

ADOLPH BALLENBERG.
